UNITED STATES PATENT OFFICE.

MELVIN HEPBURN, OF NEW HAVEN, CONNECTICUT, ASSIGNOR TO THE MARLIN FIREARMS COMPANY, OF NEW HAVEN, CONNECTICUT, A CORPORATION OF CONNECTICUT.

TAKE-DOWN GUN.

SPECIFICATION forming part of Letters Patent No. 755,660, dated March 29, 1904.

Application filed November 27, 1903. Serial No. 182,716. (No model.)

To all whom it may concern:

Be it known that I, MELVIN HEPBURN, a citizen of the United States, residing at New Haven, county of New Haven, State of Connecticut, have invented certain new and useful Improvements in Take-Down Guns, of which the following is a full, clear, and exact description.

My invention relates to certain new and useful improvements in take-down magazine-firearms of the type in which the breech mechanism is operated by a longitudinally-reciprocating handle adapted to travel parallel to the barrel and forward of the receiver. A firearm of this type is shown in the patent to Lewis L. Hepburn, No. 561,226, dated June 2, 1896, and the particular construction of the breech mechanism (which forms no part of the present invention) is fully described therein.

My invention consists in improving a certain feature of construction whereby the user is enabled to detach the barrel from the receiver with greater facility than is permissible in the construction shown in the patent above referred to.

Briefly described, my improvement resides in providing a simple, inexpensive, and effective latch mechanism whereby when it is desired to separate the barrel from the receiver or attach said parts the rod which connects the operating-handle with the breech mechanism is mechanically held out of engagement with the receiver portion, so that the barrel may be rotated without interruption.

In the accompanying drawings, Figure 1 is a perspective view of certain portions of a take-down firearm of the magazine type, said parts being partially detached. Fig. 2 is a fragmentary view, partly in section, illustrating certain details of construction. Fig. 3 is a side elevation of the rear end of the operating-rod and latch mechanism.

Since the breech mechanism of the gun forms no part of this invention, the same is not shown and need not be described. One form of breech mechanism suitable for use in such a gun as illustrated in the accompanying

drawings is, however, described and shown in full in the above-referred-to patent.

A is the forward part of a receiver, to which a barrel B may be detachably secured, the usual well-known screw-threads (not shown) being provided between said parts.

C represents the magazine.

D is an opening in the receiver A, with which the magazine C is in line when the parts are arranged in their final assembled position. The magazine C may be slid into this opening, so that it will act as a bolt to prevent the independent rotation of the barrel and magazine.

E is a reciprocating operating-handle.

F is an operating-rod for the breech mechanism. (Not shown.) This rod is secured to the handle E and is arranged to pass through the opening G and into the forward end of the receiver. When the parts are in their final position, the barrel B cannot be rotated, because the rod F, as well as the magazine, will act as a bolt.

When it is desired to remove the barrel from the receiver, the magazine C is slid forward out of engagement with said receiver, and the handle E is also slid forward until the rear end of the rod F is freed from the receiver. This will leave the barrel free to be rotated and removed. It is of course essential that the rod F shall stand in this forward position during the act of attaching or detaching the barrel. To accomplish this, I have provided simple and effective means whereby said rod is held forward mechanically, so that the barrel may be readily detached. This means comprises a frame or band H, which may be secured to the barrel B or the magazine C and which is provided with an inwardly-projecting shoulder or stud H'. In the side of the rod F is formed a longitudinal groove F', which groove toward the rear end of the rod may be deepened or cut through to form a sufficient space to permit the end of a spring-latch I to be depressed. On this latch I may have a nose I', which projects into the path of the stud or shoulder H'. The slot F' preferably terminates before it reaches

the rear end of the rod F. The stud H' is preferably removable, and the same may be formed by the blunt end of a screw projection through the frame H. The nose I' is so placed that when the handle E is pulled forward to the position indicated in Figs. 1 and 2 it will stand just ahead of the shoulder or stud H', the spring I yielding sufficiently on the forward excursion of rod F to allow said nose I' to slip over said shoulder. When in this position, the shoulder acts as a stop to prevent the rod F from slipping back, so as to project its end to the rear of the forward end of the receiver. When the barrel is screwed into place and the magazine C and rod F are in alinement with the openings D and G, respectively, the handle E may be pulled back, sufficient power being applied to overcome the resistance of the spring I, whereupon the nose I' recedes, slipping over the end of the stud H', whereupon said rod enters the receiver through the opening G.

From the foregoing it will be seen that the improvement resides mainly in providing means whereby the rod F is prevented from becoming accidentally retracted during the attachment or detachment of the barrel.

In illustrating my invention I have shown its preferred form; but it is obvious that in form and arrangement it is capable of modification without departing from the spirit and scope of my invention. In the preferred construction the spring I is a blade, with a nose formed integrally therewith, the said spring being riveted to the rod F, as shown at I².

What I claim is—

1. In a take-down firearm in which the barrel is removable from the receiver by rotation, a reciprocating operating-rod carried forward of the receiver and arranged to project into the receiver, means to withdraw said rod entirely from the receiver and a latch to tem-

porarily hold said rod in said withdrawn position.

2. In a take-down firearm in which the barrel is removable from the receiver by rotation, a reciprocating operating-rod carried forward of the receiver and arranged to project into the receiver, means to withdraw said rod entirely from the receiver and means to frictionally hold said rod in said withdrawn position, said means comprising a yielding latch and a shoulder or stud arranged to coöperate with the same. 45

3. In a take-down firearm in which the barrel is removable from the receiver by rotation, a reciprocating operating-rod carried forward of the receiver and arranged to project into the receiver, means to withdraw said rod entirely from the receiver and means to frictionally hold said rod in said withdrawn position, said means comprising a yielding latch and a shoulder or stud arranged to coöperate with the same, said latch being carried by said rod. 55

4. In a take-down firearm in which the barrel is removable from the receiver by rotation, a reciprocating operating-rod carried forward of the receiver and arranged to project into the receiver, means to withdraw said rod entirely from the receiver and means to frictionally hold said rod in said withdrawn position, said means comprising a yielding latch and a shoulder or stud arranged to coöperate with the same, said rod being grooved, said latch being carried in said groove, said stud or shoulder projecting into said groove and into the path of the said latch. 60

Signed at New Haven, Connecticut, this 24th day of November, 1903.

MELVIN HEPBURN.
